UNITED STATES PATENT OFFICE.

GEORGE HAYDEN KAISER, OF PORTLAND, OREGON.

MACHINE FOR MAKING SANITARY DRINKING-CUPS.

1,018,911.

Specification of Letters Patent. Patented Feb. 27, 1912.

Application filed July 22, 1911. Serial No. 639,978.

To all whom it may concern:

Be it known that I, GEORGE H. KAISER, a citizen of the United States, and a resident of Portland, in the county of Multnomah 5 and State of Oregon, have made certain new and useful Improvements in Machines for Making Sanitary Drinking-Cups, of which the following is a specification.

My invention relates to improvements in 10 devices for making sanitary drinking cups, and it consists in the combinations, constructions and arrangements herein described and claimed.

An object of my invention is to provide a 15 device to be stationed near the place at which the cups are to be used, the user forming the cup himself preparatory to using it.

A further object of my invention is to provide a device of few parts and comparatively 20 simple construction for enabling the operator to quickly and easily form a drinking cup.

A further object of my invention is to provide a device having a roller upon which 25 are a series of blanks to be used in making the drinking cups.

Other objects and advantages will appear in the following specification and the novel features of the device will be particularly 30 pointed out.

My invention is illustrated in the accompanying drawings forming part of this application in which similar reference characters indicate like parts in the several views, 35 and in which—

Figure 1 is a sectional view of the device from front to rear, along the line 1—1 of Fig. 2, Fig. 2 is a transverse section through the device, along the line 2—2 of Fig. 3, 40 Fig. 3 is a section along the line 3—3 of Fig. 1, and Fig. 4 is a detail view of the ratchet mechanism taken on line 4—4 of Fig. 2.

In carrying out my invention I provide a 45 main casing consisting of a bottom 1, top 2, rear 3, front 4 and sides 5 and 6 respectively. The front portion 4 terminates above the base to provide an opening 7 through which the cups are to be delivered. Within the 50 casing is a frame work consisting of the uprights 8 and 9 which rest upon the base 1 and which are secured by means of the braces 10 to the sides 5 and 6. Mounted on a shaft 11 carried by the uprights 8 and 9 55 is a reel 12 upon which is rolled a continuous ribbon or tape composed of a series of cir-

cular portions such as that shown at 13 in Fig. 2. It will be seen that these circular portions are connected at their points of tangency 13^x, so as to form a continuous 60 tape. This tape or ribbon may be made of thin sheet metal, such as sheet aluminum, tin, or even pasteboard or parchment paper.

Referring now to Fig. 1 I have shown therein a cylinder 14 which is fastened to 65 the side 3 and is provided with a spring 15 arranged to bear on a plunger 16 which has at its end a plate 17. Arranged to slide on the plunger is a cup-shaped mold member 18 which has a recess 18^x for the reception of 70 the plate 17. The cup-shaped mold member 18 is provided at its rear end with integral laterally extending arms 19 and 20 (see Fig. 3) to which are pivotally attached connecting rods 21 and 22 respectively. 75 These connecting rods are secured to the crank shaft 23, the latter being supported upon bearings 24 and 25 and being operated by a handle 26 on the opposite side of the casing. In order to guide the member 18 in 80 its movement, I provide the guide blocks 19^x and 20^x which are arranged to slide in runways such as that shown at 20^y in Fig. 3, these run-ways being formed in the metal strips 24' and 25' respectively. 85

A co-operating mold member 26 is shown in Figs. 1 and 3. This is provided with a recess 26^a and has a bar 27 (see Fig. 3) secured to it. The ends of the bar are provided with guide members 28^x and 29^x similar to the guide members 19^x and 20^x of the arms 19 and 20. The guide members 28^x and 29^x also move in run-ways similar to that shown at 20^y. A connecting rod 30 is pivotally attached to the rod 27 and to the 95 central portion of the crank shaft 23. It will be noticed that this central portion is at 180° from the connections with the rods 21 and 22. A spring 32 is attached to a pin 33 on the inner side of the side member 5, the 100 opposite end of the spring 32 being secured to an arm 34 carried by the shaft 23. Rotatably secured between the side members 8 and 9 are the rollers 35, 36, 37 and 38. The rollers 35 and 36 are held together by means of a spring 39 and the shaft 40 of the roller 36 is prolonged to a ratchet clutch 41. The latter is driven through a shaft 42 which passes through the side member 5 and has upon it a handle 43. A stop member 44 is 110 provided for the handle and a spring 45 on the arm 46 carried by the shaft 42 serves

to return the handle to its original position. At 47 (see Fig. 1) I have shown a guide member which also serves as a die for the cutter 48. The latter, as will be seen from Fig. 2, has its cutting edge on the arc of a circle so as to conform with the contour of the circular disks 13. The cutter 48 is secured to a cross bar 49 as shown in Fig. 2.

From the foregoing description of the various parts of the device the operation thereof may be readily understood.

The reel 12 is supplied with the blanks 13 and the end of the ribbon is passed between the rollers 35—36 and the guide 47 and the roller 38. The apparatus is now ready for operation. The operator first grasps the handle 43 which is resting against the stop 44 and turns the handle clockwise, until it comes into contact with the stop member 31.

This causes the tape to be drawn in between the rollers 35 and 36, and the guide member 47 and roller 38 into the position shown in Fig. 1 when the circular blank now lies immediately in front of the mold member 18.

On releasing the handle the spring 45 causes the return of the handle until it reaches the stop 44. The shaft 40 bears upon it a ratchet 40^x, while the shaft 42 is secured to a casing 41 having a pair of spring-pressed pawls 41^x arranged to engage the teeth of the ratchet 40^x, so that when the handle 43 is turned clockwise it will cause the revolution of the shaft 40 through the engagement of the spring pawls 41^x with the ratchet 40^x.

When, however, the handle is released, the pawls 41^x will ride idly over the teeth of the ratchet member. It will thus be seen that the movement of the handle in one direction will cause the plate to be drawn forward between the rollers while the movement in the other direction will have no effect. The blank now being in the position shown in Fig. 1, the operator turns the handle 26 and in doing so it causes the crank shaft 23 to revolve, thereby moving the mold member 18 forwardly and the mold member 26 rearwardly. The movement of the mold member 18 causes the severing of the blank at the connecting edge 13^x. The mold member 26 engages the center of the circular blank and presses it against the plate 17 which holds it securely. A further movement of the two mold members causes the plate to be pressed into the shape of a cup, with a flat bottom, the plate 17 entering the recess 18^x. On the release of the handle it will return to its normal position by means of the spring 32. The plate 17 which, during the movement of the two mold members together, was pushed rearwardly against the tension of the spring 15 now returns to its normal position and in so doing it pushes the molded cup out of the mold member 18, whereupon it falls to the bottom of the casing and may be removed through the opening 7.

The device is now ready for molding another cup. It will be seen that I have provided a device in which the material from which the cup is made is kept in a sanitary condition at all times prior to the actual making and use of the cup.

I am aware that sanitary cup devices have been made in which the cups are stacked together, but these devices take up considerable room, whereas, in my device a tape, provided with blanks sufficient to make a large number of cups, may be stored in the small space in the top of the device. The apparatus is comparatively simple and light and may be easily transported and set up in position near the place where the cups are to be used.

I claim:

1. In a sanitary cup making machine, a reel for holding a tape or ribbon, a pair of mold members, means for feeding a portion of the tape between said mold members, and means for causing the tape to be pressed between the mold members.

2. In a sanitary cup making machine, a reel for holding a tape or ribbon, a pair of movable mold members, means for feeding a portion of the tape between said mold members, and means for causing a simultaneous movement of said mold members to engage said tape.

3. In a sanitary cup making machine, a reel for holding a tape or ribbon, a pair of movable mold members, means for feeding a portion of the tape between said mold members, means for causing a simultaneous movement of said mold members to engage said tape, and a cutter for cutting off the portion of the tape between said mold members.

4. In a sanitary cup making machine, a reel for holding a tape or ribbon, a pair of movable mold members, means for feeding a portion of the tape between said mold members, means for causing a simultaneous movement of said mold members to engage said tape, a cutter for cutting off the portion of the tape between said mold members, and means for causing the separation of the mold members.

5. In a sanitary cup making machine, a reel for holding a tape or ribbon, a pair of movable mold members, means for feeding a portion of the tape between said mold members, means for causing a simultaneous movement of said mold members to engage said tape, a cutter for cutting off the portion of the tape between said mold members, means for causing the separation of the mold members, and means for ejecting a cup.

6. In a sanitary cup making machine, a reel for holding a tape or ribbon, a pair of movable mold members, means for feeding a portion of the tape between said mold

members, means for causing a simultaneous movement of said mold members to engage said tape, a cutter for cutting off the portion of the tape between said mold members, means for causing the separation of the mold members, means for ejecting a cup, said means comprising a plate having a stem arranged to pass through one of said mold portions, and a spring for keeping 10 said stem normally in a forward position.

7. In a sanitary cup making machine, a reel for holding a tape or ribbon, a pair of movable mold members, means for feeding a portion of the tape between said mold 15 members, means for causing a simultaneous movement of said mold members to engage said tape, said means comprising a crank shaft, and a connecting rod pivotally

secured to each mold member and to said crank shaft. 20

8. In a sanitary cup making machine, a reel for holding a tape or ribbon, a pair of movable mold members, means for feeding a portion of the tape between said mold members, means for causing a simultaneous movement of said mold members to engage said tape, said means comprising a crank shaft, a connecting rod pivotally secured to each mold member and to said crank shaft, and means for guiding the 25 30 movements of both of said mold members.

GEORGE HAYDEN KAISER.
